UNITED STATES PATENT OFFICE

2,602,504

PLASTIC WINDOW STRUCTURE

Charles J. Roos, Muskegon, Mich.

Application February 7, 1947, Serial No. 727,048

2 Claims. (Cl. 160—184)

1

This invention relates to closure or window construction, the primary object of the invention being to provide a closure or window structure wherein the sashes are constructed of plastic material and arranged so that a binding action is set up between the sashes and their guides, to cause the sashes to be retained in their various positions of adjustment, by the frictional contact between the sashes and guides.

Another object of the invention is to provide sashes so constructed that the ends thereof will overlap, to the end that a number of these sashes may be used in a window structure and the upper sashes lowered to permit of ventilation without the necessity of moving the lower sashes.

Still another object of the invention is to provide sashes that operate in guides which are pivotally supported within window frames, to the end that the sashes may be swung inwardly to facilitate cleaning thereof, and eliminating the necessity of the person cleaning the sashes working from the outer side of the building.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings:

Figure 1 is an elevational view illustrating a window supplied with sashes and sash guides, constructed in accordance with the invention.

Figure 2 is a vertical sectional view through a window frame illustrating the sashes as swung inwardly to facilitate cleaning.

Figure 3 is a vertical sectional view through a frame and sashes, mounted within the frame, illustrating several groups of cooperating sashes.

Figure 4 is an edge elevational view of one form of sash.

Figure 5 is a vertical sectional view through window sashes mounted in a window frame.

Figure 6 is a plan view of one of the pivoted sash guides curved, providing a close fit with its frame.

Figure 7 is a vertical sectional view through a modified form of the invention.

Figure 8 is a vertical sectional view through a further modified form of the invention.

Figure 9 is a transverse sectional view through a portion of the window frame, one of the window sash guides and window sashes.

2

Figure 10 is a transverse sectional view through a modified form of guide.

Figure 11 is a sectional view through a further modified form of guide.

Figure 12 is a sectional view through a window frame, showing cooperating sashes, mounted within guides in the frame.

Figure 13 is a fragmental sectional view through a modified form of guide.

Figure 14 is a fragmental perspective view illustrating a still further form of sash.

Referring to the drawings in detail, the sash as shown by Figure 2 of the drawings, comprises lower sections 5 and upper sections 6, the sections 5 and 6 being constructed of translucent plastic material, curved longitudinally and formed intermediate their ends, with ribs or enlargements 7 adapted to engage the pins 7', that extend inwardly from the guide bars, in which the sections 5 and 6 move.

These sections are slidably mounted in guideways 9 formed in the guide bars 8, the guideways 9 being arranged in parallel relation with respect to each other, and provided with depressions 8' to accommodate the ribs or enlargements 7, thereby securing the sections against movement under normal conditions.

These guide bars have upper and lower pins 10, which are positioned in openings formed in the side members of the window frames, certain of the pins of the guide bars acting as pivots for the guide bars and sashes mounted therein, should it be desired to swing the sashes and their guides inwardly to permit them to be cleaned with facility.

The lower edges of the lower sections 5 are extended outwardly, providing flanges 11, while the lower edges of the upper sections 6 are extended rearwardly at 12, providing flanges that bear against the adjacent lower sections to set up a binding action and provide a water-tight connection between the sashes.

Since the sashes are curved, it will be seen that a binding action is set up between the sashes and their guides to hold the sashes in their positions of adjustment without the necessity of providing weights, springs or the like.

The upper edges of the upper sections 6 are also extended rearwardly to rest against the upper bar of the window frame, as shown by Figure 3 of the drawings.

As shown by Figure 7 of the drawings, guideways are provided in the opposite side members of the window frame, the guide members having parallel guide ways for the reception of the side

edges of the sashes. The sashes in this form of the invention have interlocking flanges arranged along their upper and lower edges so that by raising and moving the uppermost sash section to the top of the window frame, the cooperating flanges which are indicated by the reference characters 13 and 14, will engage to move the sashes to their extended positions. Due to this construction, a tight connection is provided between adjacent sashes, and the upper sections of the sashes may be lowered without disturbing the lower sash sections, to provide ventilation.

As shown by Figure 8 of the drawings, a further modified form of sashes and sash supports is shown. In this form of the invention, the sashes are indicated by the reference character 15 and have cooperating flanged ends 16, there being provided a series of sashes arranged to provide what might be termed storm sashes.

The sashes operate in movable guide bars 17 that are fitted against the inner edges of the window frame.

As shown by Figure 6 of the drawings, the guide bar 27 is formed with ribs 9', forming guideways 28, the guide bar 27 being curved transversely and constructed of semi-rigid material so that when pressure is directed thereto by the sashes operating within the guideways 28, the guide bar will flex and be caused to closely engage the frame in which it is positioned, providing an air-tight connection between the guide bar and frame. Pins 29 extend inwardly from the guide bar and are adapted to be fitted in the openings formed in the frame, removably and pivotally mounting the guide bar within its frame.

In Figure 9 I have indicated a window frame of the usual and well known construction, altered by providing the blind stop 30, against which a guide bar, such as indicated at 17 in Figure 10, may be held. In Figure 9 the reference character 31 indicates the usual sash members, which may be removed and replaced by guide bars, such as forming the subject matter of the present invention.

The reference character 18 indicates one type of window guide member, wherein a vertical flange 19 is provided along one edge thereof to provide a stop for the guide bar 20 supported thereagainst.

Still another form of my bar is shown in Figure 12 of the drawings, the sashes 21 interengaging at their ends, so that as the sashes are extended, close fits will be provided between the flanges 22 and 23 thereof. To further provide a weather proof connection between the guide bars 24 and the sashes mounted therein, a weather strip 25 is provided along the front edge of the frame.

As shown by Figure 14, the sashes may be constructed by corrugating the same, thereby greatly strengthening the sashes. The sashes in this form of the invention are formed with laterally extended flanges that slide in grooves of guide bars, not shown.

While I have shown and described the sashes as constructed of plastic material, it is to be understood that the material of which the sashes are constructed, may be of any desired nature, providing the sashes are resilient to set up a binding action within the guide bars in which the sashes are mounted.

Having thus described the invention, what is claimed is:

1. In a closure construction, a closure frame having openings arranged adjacent to the ends thereof, guide bars having a plurality of parallel straight sash-receiving grooves fitted within the frame, pins extending from the guide members, fitted in said openings removably securing the guide members within the frame, pairs of upper and lower sash members constructed of translucent semi-rigid material curved longitudinally, the curved side edges of the sash members being fitted within the straight sash-receiving grooves of said guide receiving members, straightening said sash members, setting up a binding action between said sash members and the walls of said grooves, holding the sash members in vertical positions of adjustment, the lower edge of each sash member being curved, the adjacent upper and lower edges of adjacent sash members being overlapped providing a close fit between the sash members of each pair.

2. The subject matter as claimed in claim 1, and pins extending inwardly from the sides of the frame, and each sash member having a transversely disposed rib against which the latter pins engage to further secure the sash members against accidental displacement.

CHARLES J. ROOS.
